(57) **CLAIM**

The ornamental design for a sensor for projector for an interactive display, as shown and described.

DESCRIPTION

FIG. 1 is a top, front, left-side perspective view of a sensor for projector for an interactive display;

FIG. 2 is a top, rear, right-side perspective view thereof;

FIG. 3 is front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines shown in FIGS. 2, 6 and 8 represent portions of the sensor for projector for an interactive display that form no part of the claimed design.
